UNITED STATES PATENT OFFICE.

BERNARD McAULEY BRADFORD, OF HOPE MILLS, NORTH CAROLINA.

CRUTCH.

1,257,181.

Specification of Letters Patent. Patented Feb. 19, 1918.

Application filed November 12, 1917. Serial No. 201,603.

To all whom it may concern:

Be it known that I, BERNARD McAULEY BRADFORD, a citizen of the United States, residing at Hope Mills, in the county of 5 Cumberland, State of North Carolina, have invented a new and useful Crutch; and I do hereby declare the following to be a full, clear, and exact description of the invention, such as will enable others skilled in the art 10 to which it appertains to make and use the same.

This invention relates to an improved crutch and anti-slipping means therefor, and one of the objects of the invention is 15 the provision of an improved, simple and practical crutch construction, which may be manufactured for a small cost and sold at a reasonable profit.

Another object of the invention is the 20 provision of a simple and efficient anti-slipping means for the crutch, whereby when the crutch is used on the ice or slippery side walks and the like the crutch is prevented from slipping.

25 A further object of the invention is the provision of means whereby the anti-slipping device for sleet and ice may be retracted upwardly into the lower end of the crutch, thereby preventing the anti-slipping 30 device or spur from tearing the carpet or the like, or scratching polished floors, when the crutch is used in doors. When the spur or anti-slipping member is retracted, the usual rubber tip of the crutch may be employed to prevent the crutch from slipping 35 on floors and the like.

40 A further object of the invention is the provision of means connecting between the spur or anti-slipping member and the handle of the crutch whereby as the handle is rotated in one direction or the other the spur or slipping device may be extended or retracted.

45 In practical fields the details of construction may necessitate alterations falling within the scope of what is claimed.

The invention comprises further features and combination of parts as hereinafter set forth shown in the drawings and claimed.

50 In the drawings:

Figure 1 is a view in elevation of the crutch showing the same constructed in accordance with the invention.

Fig. 2 is a sectional view on line 2-2 of Fig. 1.

Fig. 3 is a sectional view on line 3-3 of Fig. 2.

Fig. 4 is an enlarged detail sectional view through portions of the side cut bars and the handle which connects between the bars. 60

Fig. 5 is a sectional view on line 5-5 of Fig. 1.

Fig. 6 is an enlarged detail sectional view of the lower end of the crutch.

Referring more especially to the drawings, 1 and 2 designate the side bars of the crutch, which bars are bowed as shown, and have their upper ends provided with reduced cylindrical tenons or extensions 3, to fit correspondingly shaped mortises 4 of the arm 70

rest 5. The lower ends of the side crutch bars are brought toward each other, so that they engage, and are secured together by the band 6, which is held in place by the screws 7. A rubber tip or cushion 8 is provided and this cushion has a socket 9 to receive the adjacent end portions of the side crutch bars. This rubber tip or cushion is designed to engage floors and the like to prevent slipping of the crutch. The lower 80 faces of the lower end portions of the crutch bars are provided with longitudinally extending recesses 10, (which are semi-circular in cross section), and when said adjacent faces are brought together a cylindrical 85 opening is constructed for the reception of an anti-slipping device or spur 11. The adjacent faces of the side bars from points above the handle of the crutch down to where the adjacent faces engage are provided with channels 12, for the reception of the metal strips or bars 13. The lower ends of the strips or bars 13 are secured by screws 14 to the metallic slide block or member 15, into which the spur or anti-slipping device is threaded. The upper 90 ends of the metal strips or bars are provided with suitable rack teeth 16. The handle comprises the spindle shaft 17 (which is rectangular in cross section) and the wood handle member 18, which is fitted on the rectangular spindle 17. The end portions 19 of the spindle are cylindrical, and are provided with gears or pinions 20, which mesh with the teeth 16 of the strips or bars 13, so that when the spindle is rotated in one direction or the other, the strips or bars 13 may be reciprocated downwardly 100 or upwardly. If they are moved downwardly, the spur or anti-slipping device is 105

110

designed to engage the ice or sleet, to prevent the crutch from slipping. However, when the strips or bars 13 are moved upwardly, it is obvious that the spur or anti-slipping device will be retracted, so that the rubber tip or cushion may be employed to prevent slipping of the crutch on the dry pavement or polished floors. When the spur is retracted, the crutch may be used in doors to prevent tearing or punching holes in the carpet. Secured by screws 21 on the outer faces of the side crutch bars 1 and 2 are plates 22 provided with tubular extensions 23. The outer portions of the extensions 23 are enlarged and globular shaped. These globular portions have their interiors as at 24 engaged by the ball bearings 25, which are in turn engaged by the race ways 26 of the plates 27, which are threaded on the extensions 19, there being lock nuts 28 also threaded on the extensions 19 to hold the plates 27 in place. Washers 29 are arranged between said nuts and the plates, which are provided with transverse grooves or slots 30 to receive a spanner wrench, whereby the plates may be screwed to the extensions 18. Cap or cover members 31 are threaded onto the globular portions of the extensions 23, in order to protect and cover the plates 27 and nuts 28. These caps or cover members 31 are provided with grooved slots 32 to receive the end of a screw driver, whereby they may be removed. By the provision of the ball bearings, it is to be noted that the spindle of the handles will not engage the openings through the wood side crutch bars, therefore prevent wear.

The invention having been set forth what is claimed as new and useful is:—

40 1. In a crutch, a pair of crutch side bars the adjacent faces of which having channels, the lower end of the crutch having a guide, a spur mounted therein, a block mounted and guided in the lower portions of 45 said channels and connected to the spur, rack bars mounted in said channels and having their lower ends connected to opposite sides of the blocks, a handle having a spindle mounted in bearings of the side 50 bars of the crutch, the spindle of the handle having gears meshing with the racks whereby the spur may be extended or retracted, said bearings having ball bearings 55 for the spindle, to prevent the spindle from wearing on the wood of the crutch bar.

2. In combination with a crutch having a pair of crutch side bars converging toward each other at their lower ends and means for securing their lower ends together, the adjacent faces of said secured ends having a bore formed therein, a spur pin vertically movable in said bore, the adjacent faces of the crutch side bars hav-

ing U-shaped channels extending longitudinally of the bars, rack bars movable longitudinally in said channels, a block between and connecting the lower end of said rack bars and being threaded to said spur pin, plates secured on the exterior side faces of the crutch bars and provided with ball 65 bearings, a spindle shaft having its opposite ends passing non-frictionally through the crutch bars and through said plates and engaging said ball bearings, gears on the opposite ends of said spindle shaft and meshing with the teeth of said rack bars, and a handle carried by and movable with the spindle shaft for operating the same.

3. In combination with a crutch having a pair of crutch side bars having their adjacent faces provided with longitudinally extending channels U-shaped in cross section, plates secured on the outer side faces of said bars and provided with cup members, said plates and said bars respectively having registering openings, a spindle shaft having its opposite ends extending non-frictionally through said openings, devices carried by the extremities of the spindle shaft, ball bearings between said devices 85 and the cup members, said shaft having pinions thereon, rack bars in said channels engaging said pinions, a handle fixed on the spindle shaft, the lower ends of the rack bars being connected and provided with a 90 spur pin adapted to be extended and retracted through the lower ends of the crutch bars.

4. In combination with a crutch having a pair of crutch side bars having their adjacent faces provided with longitudinally extending channels, plates secured on the outer side faces of said crutch bars, said plates and said bars respectively having registering openings, a spindle shaft having 100 its opposite ends extending through said openings and provided with pinions located in the upper end portions of said channels, said plates having means to support the spindle shaft non-frictionally in said openings, rack bars in said channels meshing with said pinions, the lower ends of the rack bars being connected and provided with a 105 spur pin adapted to be extended and retracted through the lower ends of the crutch 110 bars, and a handle on said spindle shaft for adjusting the rack bars to extend and retract the spur pin.

In testimony whereof I have signed my name to this specification in the presence of 120 two subscribing witnesses.

BERNARD McAULEY BRADFORD.
